UNITED STATES PATENT OFFICE

164,493

FILM VIEWER

Andrew L. Henkel, Hales Corners, Wis.

Application July 28, 1950, Serial No. 11,453

Term of patent 14 years

(Cl. D61—1)

To all whom it may concern:

Be it known that I, Andrew L. Henkel, a citizen of the United States, residing at Hales Corners, Milwaukee County, Wisconsin, have invented a new, original, and ornamental Design for a Film Viewer, of which the following is a specification, reference being had to the accompanying drawing, forming a part thereof.

Fig. 1 is a front perspective view of a film viewer showing my new design;

Fig. 2 is a side view, from a slightly elevated angle, showing the film viewer of Fig. 1;

Fig. 3 is a front view of the film viewer of Fig. 1; and

Fig. 4 is a rear perspective view, from an ele-

vated angle, of the film viewer of Fig. 1, and showing my new design.

I claim:

The ornamental design for a film viewer, substantially as shown.

ANDREW L. HENKEL.
